(57) **CLAIM**

The ornamental design for an alignment tool for mounting electrical switches and receptacles, as shown and described in the preceding Figures.

DESCRIPTION

FIG. 1 is a perspective view of a design for an alignment tool for mounting electrical switches and receptacles;

FIG. 2 is a front elevational view thereof;

FIG. 3 is a rear elevational view thereof;

FIG. 4 is right side elevational view thereof for which the basic design is the mirror image of the left side elevational view thereof; and,

FIG. 5 is a top plan view thereof for which the basic design is the mirror image of the bottom plan view thereof.

The broken lines are included for the purpose of illustrating environmental features and form no part of the claimed design.
